HOIST CRANE CONSTRUCTION

Robert J. Harry, Alliance, Ohio

Application January 12, 1939, Serial No. 250,576

11 Claims. (Cl. 254—188)

This invention relates to hoist mechanism, and more particularly, to new and improved hoist mechanism suitable for overhead crane utilization.

In employing hoist mechanisms suitable for handling and carrying heavy loads such as encountered in the utilization of a crane, and particularly, a traveling crane, it has been customary to employ interleaving hoist cables for supporting the load and for suitably raising and lowering the load. Hoist cables and their associated operative mechanisms must stand considerable strain, stress, and wear without dropping the load. Heretofore, in employing a pair of hoist drums with suitable sheaves, the cables have been interleaved in such a manner that reverse bends result. I have found that such reverse bends materially increase wear on the cable and thus decrease its effective and efficient operative life. I have also discovered that such a type of bend also increases the strain as well as the wear upon the sheaves, drums, and other associated hoist elements. By "reverse bends," I have reference to a relationship of cable portions wherein one drum wheel will be moved clockwise while an adjacent sheave wheel will be moved counter-clockwise. That is, a particular cable has a reverse bend when it is reeved forwardly over one wheel and is reeved backwardly with a change of direction over an adjacent wheel with the result that one wheel must rotate in an opposite direction to the other wheel whether it is a drum or a sheave. As distinguished from this, I reeve the cables in one direction such as forwardly over all of the wheels, thus eliminating reverse bends. By transverse bends, I have reference to directing or reeving the cable at substantially right angles to its previous direction.

And, it has been an object of the present invention to devise a new and improved operative arrangement of a hoisting mechanism.

Another object has been to eliminate reverse bends in a hoisting cable, and particularly, where interlocked drum gears are employed.

A further object has been to provide a hoisting mechanism having an improved cable relationship.

A still further object has been to provide an improved hoist mechanism for a four girder crane construction.

These and many other objects will appear to those skilled in the art from the drawings, the description thereof, and the appended claims.

In the drawings:

Figure 1 is a side view in elevation of a hoisting

mechanism embodying the principles of my invention and that may be utilized with a traveling crane such as shown in my copending application Serial No. 250,578, filed January 12, 1939, entitled "Hoist crane construction," Case D.

Figure 2 is a front view in elevation showing a symmetrical half of a suitable crane construction employing the hoisting mechanism of Figure 1; and

Figure 3 is a diagrammatic perspective view in elevation illustrating cable or rope interleaving of my invention, showing one pair of hoisting drums in full lines and the other in dotted lines, to which the same reference characters have 15 been added with prime suffixes.

In the drawings I have for the purpose of illustration disclosed a traveling crane arrangement such as set forth in my copending application above-mentioned. It will, however, be apparent to those skilled in the art that any suitable crane construction may be employed. The numeral 10 represents a substantially longitudinally-extending main trolley girder that is positioned adjacent opposite sides of the crane construction 20 and is provided with a track rail 11 for receiving a flange wheel 12 operably mounted in a housing portion 14 of the main trolley frame portion 13 of a hoist trolley. Carriage wheels 12 are preferably mounted at four transverse side corners of the frame 13 for operably and movably mounting such frame with respect to the support girders 10.

In like manner, an auxiliary girder 10' extends substantially longitudinally and in a spaced-apart relationship with respect to the main girders 10 and supports a track rail 11 for a suitable auxiliary trolley, if employed.

In the embodiment of my invention shown, a pair of drums 15 journaled within bearing portions 16 of the main frame are preferably mounted in such a manner that their rotative axes are on the same plane, preferably a horizontal plane, that extends transversely with respect to the 40 main trolley frame.

The drums 15 have interlocking gears 19 meshing with each other and also with drive pinions 17 positioned adjacent opposite ends of drum pairs. The pinions 17 are journaled within suitable bearings 18 and are driven by a drive shaft 18a that is adapted to extend on opposite sides of one drum pair to connect it to a similar pair on an opposite side of the machine. The transversely-extending drive shafts 18a may be connected to a suitable motivating mechanism such 55

as a spur gear motor drive, see my above-mentioned copending application.

In the simplified arrangement of the present invention, the upper and lower sheave wheels 20 and 29, respectively, are preferably operably mounted in such a manner that their rotative planes are spaced-apart with respect to rotative planes of said drums 15. The sheaves are also preferably mounted below and on or adjacent to a vertical plane representing a vertical line of interengagement between the drums of an interconnected pair. The planes representing rotative axes of the sheave wheels preferably extend in the same direction as the planes representing rotative axes of the drums 15, namely, transversely of the crane construction.

In addition to eliminating a number of sheave wheels and associated cables and connecting portions, and materially simplifying the operative construction, the present arrangement makes possible the utilization of large size cables in a highly efficient and effective manner. Also, safety features are incorporated, preventing dropping of the load in case one cable should fail.

The upper sheave wheel construction 20 is journaled within lower portions of the main frame 13 by suitable bearings 21. The lower sheave wheel 29 is rotatably mounted by a shaft 30 on vertically-extending support arms 26, 27, and 31. The support arms 26 and 31 extend downwardly through a transversely-extending lifting or ladle beam 25 and additionally support a laminated ladle hook 36 mounted thereon by a pivot pin or shaft 37. The support arm 27 is secured to the ladle beam.

A pair of connector pivotally-balanced lever arms 32 extend longitudinally of the direction of movement of the hoist apparatus and are pivotally connected at 33 on opposite sides of an upper end portion of the substantially centrally-mounted support arm 31. As shown, the sheaves 20 and 29 are preferably divided into two parts in order to receive a pair of interleaving cables, ropes, or chains 23; it will thus appear that a failure of one chain will not permit the hoist construction to drop. In effect, each so-called sheave comprises a pair of sheaves whereby a pair of cables may be employed. When I speak of cables, I include reference to ropes, chains, and other suitable means for reeving the drums and sheaves.

A cable b on the right side of the sheave and drum construction in Figures 1 and 3 and on the left side of Figure 2, is connected or dead-ended at a righthand side of the connector arms 32 at 34b, referring to Figure 1, leaves over a right portion of the upper sheave 20, viewed from Figures 1 and 3, and then turns downwardly and extends over a lefthand portion of the lower sheave 29 and again extends upwardly and connects with the righthand drum 15 viewed from Figures 1 and 3. In like manner, a cable a is connected or dead-ended to an opposite point 34a of the lefthand arms 32, viewed from Figure 1, and after interleaving, as shown, with the upper and lower sheave wheels 20 and 29, extends upwardly and connects to the lefthand drum 15 as viewed from Figures 1 and 3. The same arrangement is preferably employed for both halves of each sheave wheel group and for each of the two connector arms 32.

From the above explanation, it will appear that each half of each sheave wheel group sup-

ports a pair of cables a and b which in turn connect to their respective hoist drums.

When I speak of "leaving" or "interleaving" of the ropes or cables in the specification, I have reference to running the cables over the drums and sheaves, or in other words, reeving them. When I speak of interlocking drums, I have particular reference to the intermeshing of the gears of the drums and to the utilization of additional connections such as 17 and 18a in such a manner that the drums will rotate in synchronism and will prevent dropping the load being hoisted if one part should fail. Since the drums are separately driven by the gears 17 as well as by the intermeshing of the drum gears 15, it will be apparent that a breakage of one drive member will not cause a dropping of the load.

In addition, as will appear from the previous description, and as shown particularly in Figure 2, I preferably provide a pair of ropes or cables which reeve with pairs or half portions of upper and lower sheaves 20 and 29 as well as with the associated intermeshing drums 15.

When I speak of the axis or axes of the drums, sheaves, motors, etc., I have particular reference to the axis or axes about which they rotate.

Although for the purpose of illustration, I have shown the hoist apparatus as employed in connection with a particular type of crane construction, it will be apparent that it may be employed in connection with any suitable crane and also that many modifications, additions, and subtractions, etc., may be made in the hoist construction shown and described without departing from the spirit and scope of the invention as indicated by the appended claims.

I claim:

1. In a hoist mechanism having a suitable frame, a pair of hoisting drums operably mounted on said frame and having a portion of their axes in a side-by-side relationship, said drums having operably intermeshed drum gears, a hoisting sheave means operably mounted on said frame and having a rotatable axis extending in substantially the same direction as the above-mentioned portion of the axes of said drums, another hoisting sheave means operably mounted beneath said first-mentioned sheave means, a member for holding a load to be hoisted, support arms operably mounting said last-mentioned sheave means on said member, a carrier operably pivoted on one of said support arms and extending outwardly from its pivot point, a pair of cable means operably reeving over said drums and said sheave means, each cable means being connected at one end thereof to an extending portion of said carrier, each said cable means reeving over one of said drums and its associated sheave means in such a manner that each of said drums will turn in the same direction as its associated sheave means.

2. In a hoisting apparatus having a suitable frame, a pair of rotatable hoisting drums having a portion of their axes in a side-by-side relationship, each of said drums having a gear, said gears being operably intermeshed, said drums being operably mounted on said frame, a pair of hoisting sheaves associated with each of said drums, the rotatable axes of said drums and gears extending in the same direction with respect to each other, hoisting means operably without any reverse bends from and to end of the hoisting means reeving one of said drums and its associated sheaves for rotation in the same direction with each other, and means operably with-

out any reverse bends from end to end of the hoisting means reeving the other drum and its associated sheaves for rotation in the same direction with each other and for rotation in an opposite direction with respect to said first-mentioned drum and its associated sheaves.

3. In a hoisting apparatus, a pair of rotatable hoisting drums having a portion of their axes in a side-by-side relationship, said drums being operably intermeshed, a sheave associated with each of said drums, said sheaves having a portion of their axes in a substantially end-to-end relationship with respect to each other, said portions of the sheave axes extending in substantially the same direction as the above-mentioned portions of the drum axes, means operably reeving one drum with its associated sheave for rotation in the same direction therewith, and means operably reeving the other drum with its associated sheave for rotation in the same direction therewith, each of said reeving means being dead-ended substantially midway between said sheaves.

4. In a hoisting apparatus having a frame, a pair of hoisting drums, each drum having a gear, said drums being operably intermeshed through said gears and having a portion of their axes in a side-by-side relationship, said drums being mounted on said frame adjacent a side thereof, a sheave associated with each of said drums, said sheaves having a portion of their axes extending in substantially the same direction as the above-mentioned portions of the drum axes, means reeving each drum with its associated sheave off non-opposed outside portions of each of said drums, a lifting beam, and means operably connecting both of said sheaves to said lifting beam adjacent one and the same end thereof.

5. In a hoisting apparatus having a suitable frame adapted to be moved longitudinally, a pair of rotatable and intermeshing hoisting drums on said frame having a portion of their axes in a side-by-side relationship, such portions of the drum axes extending substantially transversely of the longitudinal direction of movement of the frame, sheaves having a portion of their axes extending in substantially the same direction as the above-mentioned portions of the drum axes, a lifting beam extending substantially transversely of the direction of movement of the frame, means reeving said sheaves with said drums, and means associated with said reeving means for connecting each of said drums to said lifting beam adjacent one and the same end thereof.

6. In a hoisting mechanism having a suitable frame, spaced-apart pairs of rotatable hoisting drums, each pair having a portion of their axes in a side-by-side relationship, each drum having a gear, the drums of each drum pair being operably intermeshed through said gears, at least one hoisting sheave associated with each drum of each pair, a lifting beam, means operably reeving a drum of one pair with an associated sheave for rotation in the same direction therewith and connecting said drum to said lifting beam adjacent one end thereof, means operably reeving the other drum of said pair with its associated sheave for rotation in the same direction therewith and for rotation in an opposite direction with respect to the first-mentioned drum and its associated sheave, said last-mentioned means connecting said other drum to said lifting beam adjacent the same end thereof as said first-mentioned drum, and means in the same manner operably reeving each drum of the other pair with

its associated sheave and connecting each drum of the other pair to said lifting beam adjacent an opposite end thereof.

7. In a hoisting mechanism having a suitable frame, a pair of hoisting drums operably and rotatably mounted on said frame and having a portion of their axes in a side-by-side relationship, said drums having gears operably intermeshed with respect to each other, a pair of hoisting sheave means for one of said drums, one sheave means of said pair being operably mounted beneath the associated drum, the other sheave means of said pair being operably mounted beneath such associated drum and beneath said first-mentioned sheave means, a pair of hoisting sheave means for the other drum of said pair, said last-mentioned sheave means pair being mounted in the same manner with respect to its associated drum as said first-mentioned sheave means pair with respect to the first-mentioned drum, the rotatable axis of each of said drums extending in the same direction as the operable axes of an associated sheave means pair, a member for holding a load to be hoisted, a carrier having a portion connected to said member, said carrier extending outwardly from its connected portion substantially transversely thereof, and means having portions operably reeving over each drum and an associated sheave means pair and being positioned on said carrier in such a manner that each of said drums will turn in the same direction as its associated pair of sheave means when actuated to raise or lower said member.

8. In a hoisting apparatus, a pair of rotatable hoisting drums having a portion of their axes in a side-by-side relation, each drum having a gear, said drums being operably intermeshed through said gears, a pair of sheaves associated with each of said drums, the sheaves associated with one of said drums having a portion of their operating axes in a substantially end-to-end relationship with a portion of the operating axes of the sheaves associated with the other of said drums, said portions of the sheave axes extending in substantially the same direction as the above-mentioned portions of the drum axes, means operably reeving one drum and its associated sheaves for rotation in the same direction with each other, and means operably reeving the other drum with its associated sheaves for rotation in the same direction with each other.

9. In a hoisting mechanism having a suitable frame, spaced-apart pairs of rotatable hoisting drums operably mounted on said frame, each pair having a portion of their axes in a side-by-side relationship, each drum having a gear, the drums of each drum pair being operably intermeshed through said gears, hoisting sheave means operably associated with the drums of one pair, hoisting sheave means operably associated with the drums of the other pair, the operating axes of said drums and sheaves extending in substantially the same direction with respect to each other, a lifting beam, means having portions operably reeving each drum of each pair with an associated sheave means and connecting each of said drums to said lifting beam adjacent an end thereof in such a manner that each drum and its associated sheave means will turn in the same direction with each other, each drum of one pair being connected to said lifting beam adjacent one end thereof, each drum of the other pair being connected to said lifting beam adjacent an opposite end thereof.

10. In a hoisting apparatus as defined in claim 4, wherein each sheave and its associated drum will rotate in the same direction with respect to each other and in an opposite direction with respect to the other drum and its associated sheave means.

11. In a hoisting apparatus having a frame, a pair of hoisting drums, each drum having a gear, said drums being operably intermeshed through said gears and having a portion of their axes in a side-by-side relationship, said drums being operably mounted on said frame adjacent a side thereof, a sheave means associated with each of said drums, both said sheave means having a portion of their axes extending in substantially 10 15

the same direction as the above-mentioned portion of the drum axes, means reeving each drum with its associated sheave means off non-opposed outside portions of each of said drums in such a manner that each sheave means and its associated drum will rotate in the same direction with respect to each other and in an opposite direction with respect to the other drum and its associated sheave means, a lifting member, and means operably connecting both of said sheave means to said lifting member adjacent one and the same side of the frame, wherein each said sheave means comprises a pair of spaced sheaves.

ROBERT J. HARRY.
